UNITED STATES PATENT OFFICE

WILLIAM KUERSCHNER, OF PITTSBURGH, AND FLOYD A. HIGERD, OF BELLEVUE, PENNSYLVANIA, ASSIGNORS TO H. J. HEINZ COMPANY, A CORPORATION OF PENNSYLVANIA

CONTAINER

Application filed June 23, 1931. Serial No. 546,192.

This invention relates to the packaging of articles ordinarily though not of necessity, fragile in nature, and consists of a partition structure within a container, capable of being used with facility and capable of affording a package of minimum bulk and of adequate security. It concerns articles of such tapered or offset shape that, when two of such articles are placed in contact, one right side up and 10 the other up side down, the cross-section of the assembly is less than the cross-sections of the two placed in contact when both are right side up. The fragile nature of the articles to which the invention ordinarily is applied requires that they be separated by partitions or other cushioning or abrasion preventing protection when within a container.

The invention is illustrated in the accompanying drawing. Figs. I and II are views 20 in elevation of two sheets of press-board or other suitable material cut to shape and capable of assembly within a container to constitute an embodiment of the invention. The two sheets are in these two figures shown in proper relative positions, in that their upper 25 edges and their lower edges are simultaneously either top or bottom edges. Fig. III is a view in horizontal section of the partition assembly within the container, the container being empty. Fig. IV is a view corresponding 30 in other respects to Fig. III but showing the container partially filled with bottles. Fig. V is a view in vertical section, on the plane indicated at V—V, Fig. IV.

The invention has to do with the packaging 35 of articles (ordinarily fragile) of tapered or offset shape and of larger cross-section at one end than at the other. A bottle, empty or filled, is such an article, and the drawing shows, typically, the packaging of bottles.

The container 1 may be understood to be 40 of suitable length, width, and height to accommodate a quantity of vertically arranged bottles B, B packed within it in a single tier. (One tier is shown; manifestly, the container might be proportioned to receive more than one superposed tier.) In packing bottles in 45 partitioned containers, it has been the practice to subdivide the space within the container by means of a partition structure made

up of sheets of suitable material slotted and fitted tightly together, to form columnar cells of fixed and uniform size from top to bottom, and of such size as to receive with snug fit the bottles to be packed. The cell, 55 accordingly, must be throughout of the maximum size. By the invention to be described, equally as great or greater security is obtained, by the shaping of the cells to the article contained in it, and by the more uniform distribution of weight throughout the container; furthermore, the bulk of the package is reduced in two dimensions, in proportion as the cross-section of the assembly of 60 bottles packed alternately right side up and up side down is less than when all are packed right side up.

Bottles are sometimes packed by thrusting them individually into conical or cylindrical shields, pokes, or wrappers of straw, excelsior, 70 or other cushioning material, and then placing them in a container in alternate right-side-up and upside-down positions. That mode of packing, however, while offering security and some reduction in bulk, is slow 75 of performance and expensive, when compared with the use of partitioned containers.

Two sets of partitions, 2 and 3, are provided, 80 equal in height, slotted and fitted together within the container, to form columnar cells—thus far the invention follows the known practice (except as to the width of the slots). Referring to Figs. I and II, the two sheets 2 and 3 are slotted at 21 and 31. The depth of these two designated slots added 85 together is as great as height of the sheets 2 and 3, to the end that when the sheets are fitted together the assembly shall be of that same height. Such fitting together of the slotted sheets we characterize interdigititation. 90 The invention is found in forming the slots, 21 and 31, of a width greater than the thickness of the material, and in providing, in addition to slots 21 and 31, other auxiliary slots, 22 and 32. These other slots extend 95 from the opposite edges of partition sheets 2 and 3 to the intervening necks 23 and 33; they are aligned with the center lines of slots 21 and 31, and they also are of width greater than the thickness of the material. As par- 100

tition structures of this sort have ordinarily been made, the width of the slots 21 and 31 has been as great as the thickness of the sheet material. It has been disadvantageous to 5 form them to greater width. The slots as they are formed in the practice of this invention are wider than the sheet material is thick, and of such width as is necessary to accommodate the article being packed. As 10 shown in Figs. III, IV, and V the slots are three times the thickness of the sheet material, and such proportioning is adequate to the packaging of the articles shown. In the assembly the auxiliary slot 22 (32) of one 15 partition co-operates with interdigitating slot 31 (21) of the companion partition to define a vacant space *s* (Fig. III), and in consequence, the component members of the partition structure assembled within the container may be tipped one relatively to another, and each columnar cell may thus be 20 brought to tapered shape, having at its two ends the cross-sectional areas of the squares *m* and *n*, indicated in broken lines in Fig. 25 III; and, turning to Figs. IV and V, it will be perceived that thus the cells of the assembly may be made alternately tapering, in chequered pattern (as seen from above); and that bottles may be packed (as shown in Figs. 30 IV and V) in alternate erect and inverted positions, with minimum loss of space and, consequently, with maximum security. Consideration of Fig. V will show that, where- 35 as in the container of the invention, the wide slots in the partition pieces permit the partition cells to adjust themselves to the shape of the bottle to the extent that the bases of adjacent bottles can overlap in vertical lines approximately one-half the difference be- 40 tween the greatest and the least cross section of the bottle, less the thickness of the partition, if the cells were of uniform dimensions throughout their heights the bottles would necessarily stand apart at an interval as great 45 as the thickness of the sheet material: thus the gain in length and width of container and in security by the better fit of the packing around the bottle.

Incidentally, it should be remarked that 50 the tipping of the partition sheets incident to the practice of the invention does not necessarily involve any distortion of the sheet from its plane-surfaced extent; and, while such distortion is ordinarily desired 55 (of Fig. V), the distortion is not localized in the relatively weak necks 23 and 33, but is distributed along the relatively strong marginal portions of the sheets.

It has been said that the sheet material 60 may be paper. It ordinarily will be the cellular material built up of alternate layers of smooth and corrugated paper; but it need not be paper; it may be any sheet material having the desired elasticity.

65 We claim as our invention:

1. A container including in its structure two partition walls of sheet material lying in angularly extending planes, slotted from opposite edges inwardly and by such slotting interdigitated, one of said walls being provided with an auxiliary slot formed opposite to and in alignment with the interdigitating slot first alluded to and in the assembly co-operating with the interdigitating slot of the other partition wall to define a vacant space of columnar form, whereby one of the walls may be tipped relatively to the other. 70
2. The structure of claim 1, all of the slots being in width at least three times as great as the thickness of the sheet material. 75
3. A container including in its structure two partition walls of sheet material equal in height, lying in angularly extending planes, the two said walls being slotted from opposite edges inwardly, each with one of two slots whose aggregate depth is as great as the common height of the said walls, and the two said walls being by such slots interdigitated, one of said walls being additionally provided with an auxiliary slot formed opposite to and in alignment with the interdigitating slot first named and in the assembly co-operating with the interdigitating slot of the other partition wall to define a vacant space of columnar form, whereby one of the walls may be tipped relatively to the other. 80

In testimony whereof we have hereunto set our hands.

WILLIAM KUERSCHNER.
FLOYD A. HIGERD.
